(57) **CLAIM**

I claim the ornamental design for a lock, as shown and described.

DESCRIPTION

FIG. 1 is a front perspective view of a lock showing my new design;

FIG. 2 is a top view of the lock of FIG. 1;

FIG. 3 is a front view of the lock of FIG. 1;

FIG. 4 is a rear view of the lock of FIG. 1;

FIG. 5 is a bottom view of the lock of FIG. 1;

FIG. 6 is a right side view of the lock of FIG. 1; and,

FIG. 7 is a left side view of the lock of FIG. 1.

The broken lines shown are for illustrative purposes only and form no part of the claim. Where broken lines abut a claimed surface it is understood that those broken lines represent an unclaimed boundary between claimed and unclaimed surfaces. None of the broken lines form any part of the claimed design.
